VELOCITY-SELECTION-TYPE PICKUP TUBE

George A. Morton, Princeton, N. J., assignor to
Radio Corporation of America, a corporation of
Delaware

Application June 28, 1946, Serial No. 679,929

4 Claims. (Cl. 315—11)

1

This invention relates to electron tubes and particularly to tubes in which the electrons emitted by the target are separated into relatively high and low velocity streams and either the one or the other is utilized for production of an image or other signal indication, and is an improvement of the electron tube disclosed in my joint application with Gardner L. Krieger, filed June 28, 1946, Serial No. 679,928.

It is an object of the invention to provide an electron pick-up tube in which the electrons emitted by a screen are velocity-selected.

It is another object of the invention to provide an electron pick-up tube for transmitting to a distant point electric current which varies in accordance with the velocities of the electrons emitted by the scanned elemental areas of the target on which an image is focused.

Another object of the invention is to provide an electron pick-up tube in which the target is scanned by a cathode ray beam for production of electrons, varying the velocities of the electrons in accordance with a potential image thereon and selecting electrons of predetermined velocity range for multiplication.

Other objects of the invention will appear in the following specification, reference being had to the drawings, in which:

Figure 1 is a section through a tube of the invention.

Figure 2 is a section through a tube of a modification.

Figure 3 contains graphs of the velocity distribution of electrons at the selector grid.

Referring to Fig. 1 of the drawing, the tube comprises a gass or other envelope 1, which generally would be highly evacuated. In one end of the tube is a radiation sensitive target or sensitized screen T and at the other end a plate or diaphragm electrode 2 containing an aperture 3 through which the electrons of the target areas are scanned, as in the known dissector tube.

The target T may be any of various types, but by way of example I have illustrated a target whose resistance is varied by incident radiation from an object to be televised. This target consists of a body 4 made of a sheet of material having a positive or negative resistance characteristic, depending upon the desired method of operation. For photo images it may be made of a photo conductor, such as activated thalium sulfide, copper oxide, etc., particularly for incident radiation of near infrared, visible light or ultraviolet energy. For far infrared or heat energy incident thereon, the target may be made

2

of a thermo-sensitive material such as thin glass, the titanates of barium and strontium, titanium oxide or other suitable material. All these materials have a negative coefficient of resistance.

5 Composite films can be processed to exhibit a positive coefficient of resistance with change in temperature. That is, metals may be combined with the materials having negative coefficients of resistance to obtain a target of positive coefficient. It is also a known phenomenon that titanium oxide (Ti_2O_3) has a critical temperature below which it has a positive coefficient and above which it has a negative coefficient. This can be used either alone or in combination with other materials for the resistance body.

10 On the side of the target body 4 facing the end of the tube is a very thin conducting film 5, which may be transparent to the radiant energy utilized, as when the sensitive layer is a photo conductor, or it may convert radiation to heat, which is conducted to the sensitive layer. On the opposite surface is placed a sensitive mosaic 6 of small discrete areas capable of emitting primary electrons, photoelectrons, or secondary electrons.

15 20 25 30 By way of example, in Fig. 1 a target has been shown capable of emitting secondary electrons under bombardment of the cathode ray beam from gun G. This gun may be of standard construction, such as disclosed in the application of Paul K. Weimer, filed September 16, 1944, Serial No. 554,494, now U. S. Patent 2,433,941. The cathode may be connected to the negative terminal of the voltage supply. The beam from the gun passes through an appropriate aperture 7 in the electrode 2. When using the gun for bombarding secondary electrons from the target, the sensitive discrete areas constituting the mosaic of the target may be silver-magnesium alloy, for example.

35 40 45 Between the target T and the electrode 2 are placed a plurality of electrostatic ring electrodes, such as 8, 9 and 10. These are for accelerating the electrons emitted by the target to the electrode 2. Closely adjacent the electrode 2 on the opposite side is a selector electrode 11, shown in the form of a screen or grid. Beyond this grid, and opposite the aperture 3, is placed the first dynode 12 of an electron multiplier. As many stages of multiplication as desired may be used, but I have shown additional dynodes 13, 14 and 15 and a collector 16 of a four-stage multiplier. Any form of multiplier may be used and the one illustrated is diagrammatic only.

50 55 To scan the beam from gun G over the mosaic of the target T, and also to scan the secondary

electrons emitted by the target **T** over the diaphragm **2** for successive passage of electrons through the aperture **3**, I provide a deflecting coil unit **17**, which may have the usual two coils arranged at right angles, commonly referred to as vertical and horizontal deflection coils, connected to a saw-tooth or other generator (not shown). These are well known and the illustration is diagrammatic only. Around the deflecting unit is placed the electromagnetic focusing coil **18** for producing a uniform magnetic field for focusing the beam electrons on the mosaic and the bombarded secondary electrons emitted by the target on the diaphragm **2**.

At the target end of the tube **1** may be placed the unit **19** for projecting an image of an object on the target through the end of the tube by light, infrared, thermal, or other desired incident energy. Assuming, by way of example, that thermal energy is to be used to produce the image of the object on the target, the end **20** of the tube may be made of silver chloride, so that the thermal energy will pass sufficiently through to the target. This end **20** is suitably sealed to the envelope **1** to form a vacuum-tight joint. The lenses may be made of rock salt, for example.

Lifter plates **21**, **22**, such as disclosed in Iams Patent 2,213,177, August 27, 1940, separate the beam electrons from the secondary electrons accelerated from the target mosaic to the anode **2**. These would be connected to direct current potentials, as will be understood by those skilled in the art.

The positive terminal of the direct current voltage supply may be connected to ground and various potentials may be applied to the other terminals, as would be understood by those skilled in the art. However, I have indicated suitable potentials on the drawing by way of example.

Assume that the target **T** is being scanned by the beam from gun **G** and that no radiant energy is incident on the target. The areas while under beam impact will emit secondary electrons substantially uniformly, but the electrons will be emitted with a range of velocities, as indicated by graph A. These secondary electrons are accelerated toward the electrode **2**, producing uniform current flow through the target body **4**. If there are n elemental areas of the mosaic, one can visualize n electrical resistance paths transversely across the target body **4** and there will be a voltage drop in each path equal to the resistance times the electron current. No radiation being incident on the target **T**, the plurality of paths have the same resistance and the electron currents therealong will be substantially uniform. The elemental areas will thus have the same potential, but the velocities at the selector grid **11** of electrons emitted by each elemental area will have the range or velocity distribution shown by graph A of Fig. 3.

The potential on selector grid **11** is adjusted to a potential such that all electrons having a velocity below V_1 of graph A cannot pass grid **11** and substantially all the electrons emitted are reflected and collected by the various electrodes between the anode **2** and the target **T**. The multiplier output from collector **16** will then be zero.

Now, assume that an image of an object is produced on the target by incident thermal energy. Since the target body **4** has a negative coefficient of resistance, the resistance of the body **4** in the multiplicity of paths now becomes less, the resistance of each path depending upon the amount

of energy incident upon the area through which the path passes. Each path will have a voltage drop equal to the resistance times the electron current, the white areas thus having lower potentials than the gray areas and the gray areas less than the "black" areas. Thus, there will be a potential image over the mosaic corresponding to the image produced by the incident thermal energy. The velocity distribution at the selector grid **11** for areas receiving no incident energy ("black" areas) will, as before, be that given by graph A of Fig. 3, because the potential of these areas did not substantially change. The electrons emitted from areas receiving the most thermal energy ("white" areas) are more negative to the grid **11** and their velocities relative to it are given by graph B. Those areas receiving intermediate amounts of energy will be intermediate the values of graphs A and B, such as shown by graph C.

All electrons having velocities above the value V_1 pass through aperture **3** and the selector grid **11** to the first dynode **12** and the total number passing through the selector for the "white" areas is proportional to the area $V_1 Q_1 V_2$. For areas receiving intermediate incident energy ("gray" areas), the energy input to the multiplier is indicated by area $V_1 Q_2 V_3$. For areas receiving no thermal energy, the multiplier input will be zero. Thus, the input and output of the multiplier varies with the incident energy on the target.

The field of deflecting unit **17** scans the electrons emitted by the mosaic through the aperture **3**, as in the known disector tube. The image on the target is dissected and the multiplied signals, with or without amplification, may be transmitted from the collector electrode **16** to any desired point for reproduction of the image in known ways.

In Fig. 1 the aperture **3** may be of such size as to define the picture elements, or the beam spot may define it and the aperture **3** may be made larger than the size of a picture element.

In the modification of Fig. 2, the electrons emitted by the target mosaic or sensitized screen are photoelectrons instead of secondaries. These are produced by ultraviolet energy from a lamp or generator **23**, such as a mercury lamp of ring or semicircular shape, or other radiation which does not conflict with the radiation being imaged. The scanning coils and focusing coils may be divided into two parts **24**, **25** and **26**, **27**, respectively, so the lamp may be placed in position to project its rays into the tube. The anodes **8**, **9** and **10** may be sand-blasted to produce diffused reflection of the ultraviolet rays to the mosaic surface **6**, which in this case may be activated manganese, potassium or caesium.

In this modification I have shown, by way of example only, a construction in which the low velocity electrons are selected and utilized. This is accomplished by operating an electron mirror **28** at some potential that will collect all electrons having a volt velocity equal to, or greater than, V_4 in Fig. 3. The lower velocity electrons scanned through aperture **3** cannot land on the mirror and are reflected to the first dynode **12**. Electron multiplication is accomplished in the way described in connection with Fig. 1. The higher velocity electrons land on mirror **28** and are not utilized. The number of electrons passing into the multiplier in this case is given by the area $V_4 Q_3 V_5$ for the "white" areas. The multiplier input for an area having incident energy of some particular value between black and white would

be given by graph D and the number of electrons in the multiplier input is given by the area $V_4 Q_4 V_6$.

The various parts of Fig. 2 that are similar to those of Fig. 1 have been given the same reference characters and they need not be described in detail.

I claim:

1. An electron discharge device comprising, an envelope, a target electrode mounted within said envelope, said target electrode formed of a radiation sensitive material having a specific electrical resistance which is a function of radiant energy impinging thereon, a conductive electrode in contact with one surface of said target electrode, an electron emissive material on an opposite surface of said target electrode, a collector electrode within said envelope, and a selector electrode mounted between said collector electrode and said target electrode, means including an electron gun for initiating an electron emission from said electron emissive target material, lead means connected to said conductive electrode for joining said conductive electrode to a source of potential, electrode means within said envelope for accelerating electrons from said emissive target coating toward said collector electrode, means for focusing radiation from a source of radiant energy upon said target electrode for changing the specific resistance of said target material, and lead means connected to said selector electrode for joining said selector to a second source of potential for blocking electrons from those portions of the emissive target coating in contact with the target portions not subjected to radiations from said source of radiant energy.

2. An electron discharge device comprising, an envelope, a target electrode mounted within said envelope, said target electrode formed of a radiation sensitive material having a specific electrical resistance which is a function of radiant energy impinging thereon, a conductive coating on one surface of said target electrode, a secondary electron emissive material on an opposite surface of said target electrode, a collector electrode within said envelope, and a selector electrode mounted between said collector electrode and said target electrode, an electron gun means for forming an electron beam along a path intercepting said target electrode, means for scanning said electron beam over the surface of said secondary electron emissive material to initiate a secondary emission from said target, lead means connected to said conductive target coating for joining said coating to a source of potential, electrode means within said envelope for accelerating secondary electrons from said emissive target coating toward said collector electrode, means for focusing radiation from a source of radiant energy upon said target electrode for changing the specific resistance of said target material, and lead means connected to said selector electrode for joining said selector to a second source of potential for blocking electrons from those portions of the emissive target coating in contact with target portions subjected to radiations from said source of radiant energy.

3. An electron discharge device comprising, an envelope, a target electrode mounted within said envelope, said target electrode formed of a radiation sensitive material having a specific electrical

resistance which is a function of radiant energy impinging thereon, a conductive coating on one surface of said target electrode, a photosensitive material on an opposite surface of said target electrode, a collector electrode within said envelope, and a selector electrode mounted between said collector electrode and said target electrode, means for initiating emission from said photosensitive target material, an apertured plate electrode positioned between said collector and said target electrode, means scanning said photoemission over said apertured plate electrode, lead means connected to said conductive target coating for joining said coating to a source of potential, electrode means within said envelope for accelerating electrons from said photoemissive target material toward said collector electrode, means for focusing radiation from a source of radiant energy upon said target electrode for changing the specific resistance of said target material, and lead means connected to said selector electrode for joining said selector to a second source of potential for blocking electrons from those portions of the photoemissive target material in contact with target portions not subjected to radiations from said source of radiant energy.

4. An electron discharge device comprising, an envelope, a target electrode mounted within said envelope, said target electrode formed of a radiation sensitive glass material having a specific electrical resistance which is a function of radiant energy impinging thereon, a conductive coating on one surface of said target electrode, an electron emissive material on an opposite surface of said target electrode, a collector electrode within said envelope, and a selector electrode mounted between said collector electrode and said target electrode, means for initiating emission from said electron emissive target material, an apertured diaphragm electrode positioned between said collector electrode and said target electrode, means for scanning said electron emission over the surface of said apertured diaphragm electrode, lead means connected to said conductive target coating for joining said coating to a source of potential, electrode means within said envelope for accelerating electrons from said emissive target coating toward said collector electrode, means for focusing radiation from a source of radiant energy upon said glass target electrode for changing the specific resistance of said target material, and lead means connected to said selector electrode for joining said selector to a source of potential for blocking electrons from those portions of the emissive target coating adjacent target portions subjected to radiations from said source of radiant energy.
